UNITED STATES PATENT OFFICE.

EMILE MAERTENS, OF PROVIDENCE, RHODE ISLAND.

PROCESS OF AND APPARATUS FOR REMOVING FATTY MATTERS FROM WOOL.

SPECIFICATION forming part of Letters Patent No. 545,899, dated September 10, 1895.

Application filed July 14, 1894. Serial No. 517,573. (No model.)

To all whom it may concern:

Be it known that I, EMILE MAERTENS, a citizen of the United States, residing at Providence, in the county of Providence and State 5 of Rhode Island, have invented certain new and useful Improvements in Processes of and Apparatus for Treating Wool and Other Animal Fibers; and I do hereby declare the following to be a full, clear, and exact description 10 of the invention, such as will enable others skilled in the art to which it appertains to make and use the same, reference being had to the accompanying drawings, and to letters and figures of reference marked thereon, 15 which form a part of this specification.

This invention relates to a new process and apparatus for treating raw wool and similar animal fibers with naphtha, benzine, or similar products from petroleum, bisulphide of 20 carbon, ether, or similar fat solvents, for the purpose of freeing wool and similar animal fibers from fatty, waxy, resinous, and other matter or impurities which are soluble in such solvents without having to subject said fibers 25 to the destructive action of hot soap or alkaline solutions in order to put them in workable condition. I am aware that the treatment of wool with fat solvents is not new, and that several unsuccessful attempts have been made 30 to do this work on a commercial scale. The object I have in view is to leave the wool in the best workable condition and without injury to the fiber; to do the work quickly, thoroughly, cheaply, and safely; to operate upon 35 large quantities, and to obtain the by-products of this treatment in the best possible condition, so as to make the cleansing of animal fibers a source of profit instead of an expense.

40 My invention consists in the novel process for cleansing wool or other animal fibers.

It also consists in the new and improved apparatus employed for cleansing said fibers and embodying the process referred to, all as 45 will be more fully hereinafter set forth and claimed.

Some of the characteristic features of my invention are as follows: The several digesters and tanks in the system independently 50 intercommunicate, the solvent employed is moved by compressed air or any other suitable gas, and the first impregnation of the

fibers with it is by preference made *in vacuo*, and the process then continued at atmospheric or higher pressure. The whole process is carried on under seal, and consequently the loss of solvent is minimized and the operation made comparatively safe and perfectly healthy. The fibers are dried by heat and vacuum or by heated air drawn or aspirated through them. The operation is not started with pure solvent, but with a solvent which has been previously used or is charged with wool-fat, because I have discovered that certain constituents of wool-fat are excellent 65 solvents for the resinous, waxy, tarry, and glutinous impurities contained in animal fibers, and that, therefore, a partially-saturated solvent removes these impurities from the fibers more completely than a pure solvent, and thus the cost of redistillation is minimized; but notwithstanding this the sundry solvent baths used are so applied that each preceding bath is followed by a less-saturated bath, and the fibers are rinsed with pure solvent, so as to insure the complete removal of any adhering fatty, resinous, tarry, or glutinous impurities. The solvent adhering to the fibers is distilled off by heat and vacuum, thus insuring its removal at a comparatively 70 low temperature, and the last traces of solvent are removed by drawing or aspirating air or air and steam through the fibers. All this work is accomplished without disturbing the fibers from the time they are put in the digesters until they are ready for the final rinsing with water to free them from such impurities as are insoluble in the solvent used to remove their fatty and resinous impurities.

The exact number of steps used in the freeing of fibers from their fatty and resinous impurities according to the present invention may vary somewhat, according to the nature and condition of the materials to be operated upon, but they are generally and by preference as follows: The fibers are inclosed in a series of digesters (say four, more or less) and dried by drawing or aspirating warm air through them until the mass of fibers operated upon is warmed up sufficiently to insure the vaporization of the moisture, which they still contain, under the influence of a vacuum, which is then applied. The fibers having been freed from moisture, as indicated, find them-

selves *in vacuo*, and when the pump producing it has been stopped the first digester of the series is put into communication at its top with a reservoir containing solvent, which is 5 partially saturated with wool-fat extracted from fibers in previous operations and filled therefrom. Communication is now established between the bottom of the first digester and the top of the second one, and, by the influence of the vacuum existing in the second digester and of compressed gas or air applied at the top of the first digester, the solvent is 10 driven out of said first digester and pressed and blown out of the fibers which it contains, 15 in liquid form, over and into the second digester. The top of the first digester is now put into communication with a reservoir containing solvent which has been used in previous operations, but which is less saturated 20 than the one first used, and by the application of compressed air or gas inside of the reservoir containing said solvent it is driven to the top of said first digester. The bottom of digester No. 2 being now put in communication with 25 the top of digester No. 3, the vacuum in the latter and the compressed air or gas contained in digester No. 1, and which is forced out into digester No. 2 by the new incoming solvent just mentioned, forces the first solvent used 30 out of digester No. 2 into digester No. 3 in the same manner that it was driven from digester No. 1 into digester No. 2.

The operation just described is continued until each of a series of solvents, all of the 35 same nature, but each succeeding one of a lesser degree of saturation than the preceding one, and finally pure solvent, have been driven from one digester into another and through the whole series of digesters in the manner 40 indicated and by alternate applications of solvent and compressed air or gas at the top of the digesters, and until each lot of solvent has reached its destination, back into the 45 sundry storage-tanks provided for solvents of different degrees of saturation.

As fast as any of the digesters has had its last charge of solvent emptied into its neighbor or into the storage-tank provided for it, it is put into communication at its bottom 50 with the solvent-tank containing the solvent with the least degree of saturation, (except pure solvent,) and by the application of compressed air or gas to the top of said digester the solvent, with which the fibers are still 55 soaking, is nearly all pressed out and driven out of said fibers, in liquid form, into the storage-tank mentioned.

The communication between the storage-tank and the digester having been cut off at 60 the conclusion of the last operation, and as the fibers contained in the digesters have still some solvent adhering to them, it is put into communication at its top with the storage-tank for pure solvent, but through the intermediary of a vacuum-pump and a condenser. Steam is now applied to a heater contained 65 in the bottom of the digester and, either by

trickling down upon the latter or by radiation of heat, some of the solvent is immediately volatilized, and by the action of the 70 vacuum-pump these vapors are drawn upward through the mass of fibers and cause the volatilization of more solvent, and by the aid of said vacuum-pump the distillation of the residuary solvent adhering to the fibers is carried on at a rapid rate and at a low temperature, and by the aid of the condenser it is 75 delivered into the storage-tank without any appreciable loss.

When the distillation of the solvent is completed, (which is indicated by a vacuum-gage,) and as it is difficult to obtain solvent free from odorous impurities which do not pass over at the temperature used in the operation just described, a current of air, or of air and 85 steam mixed, is drawn or aspirated through the fibers contained in the digester and they are thus deodorized. The fibers being now freed from their fatty and resinous impurities are removed from the digester to be further 90 cleansed with water prior to their utilization in the regular process of manufacturing.

In order to illustrate my improvements, I have prepared the accompanying three sheets of drawings, which together represent a single side view or elevation of the complete apparatus employed for carrying out my improved process herein described. In order, also, that the representation of the apparatus be sufficiently large to clearly show the several elements constituting it, the drawing is practically one complete figure or view and is to be so considered, the same, however, being divided, for convenience, into three sections or parts, each of said sheets bearing one 105 part—that is to say, Sheets 1 and 3 illustrate the left and right sections, respectively, and Sheet 2 the center section.

Again referring to the drawings, A', A², A³, and A⁴ indicate the four closed digesters in 110 which the wool or fibrous materials are confined while being subjected to the several treating operations forming the subject of my present invention.

B', &c., to B⁵, inclusive, Sheets 2 and 3, 115 indicate a series of six storage-tanks for solvents, arranged to communicate with said digesters.

F, Sheet 3, indicates the overflow-tank communicating with said digesters and storage-tanks. The air or gas discharged from the digesters and tanks of the system also passes into tank F and from the latter to the trap-tank M. It also receives the drip from all the mains.

E, Sheet 1, indicates a grease-tank for containing the grease extracted from the saturated solvents.

H indicates a still in which the saturated solvents are rectified or distilled.

I, Sheet 1, is a settling-tank in which the saturated solvents are allowed to settle before being run into the still H.

L, Sheet 1, is a condenser used for condens-

ing the vapors of solvents in the still H and in the digesters A' to A⁴.

5 G, Sheets 1 and 2, indicates a compressed air or gas tank for storing compressed air or gas.

W', Sheet 2, is a heater which can be used for heating air or gas adapted to be used in the digester A', &c.

W W² indicate gas-generating apparatus 10 wherein either acid gases or vapors are produced for use in the digesters.

K, Sheet 1, is a filter for separating the saturated solvent from the settling which accumulate in the settling-tank I.

15 M, Sheet 3, is a trap-tank through which the air or gas from several digesters and tanks escape through a water-seal into the atmosphere.

M', Sheet 1, is a tank into which the acid 20 vapors generated in W W² are condensed.

C is a compressor for compressing air or gas for storage in tank G.

D D' are vacuum-pumps used for making a 25 vacuum and drawing or aspirating air, gases, or vapors through and from the digesters.

Referring to Sheet 3, the digester A⁴ is one of the receptacles for containing the fibers to be cleansed. Each digester is composed of a cylindrical shell having a bottom head a, a 30 top head a' with an upwardly-extending hollow neck a², a cover a³, upper and lower doors b b, a perforated false bottom c, under which is placed a heater a⁶ having water and steam inlets at c² and water and steam outlets at c³. The bottom head has a central discharge-nozzle c⁴ and a steam-inlet c⁵. The neck a² of the 35 digester-head has four nozzles—viz., a nozzle d, connected with the dry vacuum-main 6 by valved branch e, a nozzle d', connected with 40 the wet-vacuum main 7 by a valved branch e', a nozzle d², connected with the compressed air or gas main 9 by valved branch e², and a nozzle d³, connected with the air or gas outlet-main 8 by a valved branch e³. In addition to 45 these the top digester-head connects at f, through corresponding upright valved pipe f, with the filling-main 1, and at f', through a valved branch f', with the supplementary upper main 2, which arrangement permits the 50 solvent to be forced from the bottom of any of the digesters to the top of any of the others. The dry-vacuum main 6 is connected with the 55 vacuum-pump D, and is also connected with each digester by a corresponding branch pipe e, in each of which is located a valve v. The wet-vacuum main 7 is connected indirectly with the vacuum-pump D', and is also connected with each digester by a corresponding branch pipe e', in each of which is located a 60 valve v'. The compressed air or gas main 9 connects with the compressor C. Said main connects with each digester by a corresponding branch pipe e², in each of which is located a valve v². The discharge or air or gas outlet main 8, which is also called the "overflow-main," is connected with each digester by a

branch pipe e³, in each of which is located a valve v³.

On Sheet 2 are represented vertical branch pipes f leading from the filling-main 1. These 70

are used for carrying the solvent to the corresponding inlet f of any individual digester from any of the storage-tanks, the same being effected by simply manipulating any of the valves k k', according to the digester that is 75

to be filled and the storage-tank from which the solvent is to be taken. The inlets 4^a to the storage-tanks communicate each with the 80

drain-main 4 through a valve v⁵, the drain in turn communicating with each of the bottom 85

outlets c' of the digesters through valves v⁶. Each of the inlets 11 to the storage-tanks 90

communicate with the compressed air or gas main 9 through a valve s, and the outlets 12 from the storage-tanks communicate with the 95

overflow or air or gas outlet main 8 through the valves s'. Said main 8 is also intended 100

to take care of the drains from the sundry mains and of any overflow which may occur from any of the sundry tanks or digesters. 105

The overflow-tank F communicates at its bottom, through a valved connection 10^a, with a small main 10, through which latter all the storage-tanks intercommunicate. The 110

storage-tanks are provided with bottom outlets 1^a and valved connections 10^b, and through 115

which piping, &c., these tanks are originally filled with solvent from tank-cars outside of the building. At the top of the overflow-tank 120

F the air or gas outlet or overflow main 8 enters, the air or gas outlet from said tank being through the valved pipe 8^a, the latter extending and entering the trap-tank M. The 125

said overflow-tank F communicates with the compressed air or gas main 9 through a riser 10^a, and the valve b³ on riser 8 shuts off the 130

overflow-tank from the whole system whenever compressed air or gas is introduced into 135

said tank to remove its contents to one of the storage-tanks, in which case the valve x¹⁰ on 140

riser 8^a is also closed and the by-pass valve x on the branch-connecting risers 8 and 8^a is 145

opened, thus relieving the system by direct communication with the trap-tank M. The 150

grease-tank E connects with the wet-vacuum 155

main 7 through its valve b⁴ and with the compressed air or gas main 9 through valve b⁶. Atmospheric air or steam is admitted at i, 160

and through valve r⁴ the grease-tank communicates with the bottom of the still H 165

through piping 15.

On Sheet 2 are shown pipes c⁴, each connecting the corresponding bottom digester-head with the drain-main 4 through a valve 170

v⁶, and also connecting with the supplementary lower main 3 through valves v⁷ and v⁸. The main drain 4 communicates with the 175

inlets to storage-tanks through the several valves v⁵. The compressed air or gas inlets 11 to the several storage-tanks are through 180

the valves s, and the air or gas outlets 12 from the tanks are through valves s'. Branches

from main 4 are shown entering the storage-tanks at 4^a. The outlet from the condenser L is through valve v^9 and piping 14, the latter communicating with the sundry storage-tanks 5 through the corresponding valves v^{10} . The still H is fed from the settling-tank I through the series of valves r' , piping 18, and valve r^3 . The vapor-outlets from the still are at 13^a, and the grease-outlet from said still is through 10 valve r^4 and piping 15. The valve r^5 , on upright pipe 20, admits solvent out of the storage-tanks into the top of the settling-tank I. Valve r^7 communicates with the bottom of the settling-tank and through the piping 21 15 with the top of filter K, the latter communicating at its bottom with the storage-tanks. The gas-generator W W² communicates with the atmosphere outside of the building through valve r^8 and piping 16^b. It also communicates 20 with the heater W' through valves r^9, r^{10} , and branch piping 16^a and through the heater or piping 16^c with the bottom of the several digesters through the main 16.

On Sheet 1 is shown the manner of connecting the vaporized-solvent main 13 to the condenser L. The main enters the condenser through the valve r . It runs from the discharge end of the vacuum-pump D and connects therewith through pipe 13^b and carries 25 to the condenser the vaporized solvent, which is drawn from the digesters or still by said pump through the main 6. The vaporized solvent from the still H can go to the condenser direct by opening valve r^{10} and closing valve r^{11} , or it can go through the pump D by opening valve r^{11} and closing valve r^{10} . The solvent leaves the settling-tank I through 30 valves r' and enters the still H through piping 18 and valve r^3 , compressed air or gas being admitted to said tank through valve w' and the air or gas outlet from said tank being through valve w^2 . The compressed air or gas tank G is filled by the compressor C through 35 the main 9 and valve x . The digesters communicate with the dry-vacuum main 6 through the four valves v and with the wet-vacuum main 7 through the four valves v' , as before stated. The compressed air or gas inlet to the digesters is through the valves v^3 40 via main 9 9^a and the air or gas outlet from the digesters is through the valves v^4 . The digesters are filled from the storage-tanks through the piping, which communicates with the filling-main 1 and enters the upper digesters-head at f through piping f and interposed valves k. The digesters intercommunicate through the supplementary mains 3 and 2 through the valves x', v'', v^8 and upright pipe 2^a. An air communication 45 between the digesters is established through valves x^2 . The trap-tank M is simply a tank adapted to be partially filled with water, into which dips a branch 8^a of the outlet-main, leading from the overflow-tank F. By this 50 arrangement it will be seen that the air or gas which escapes through this pipe 8^a has to pass through water before it escapes into the

atmosphere at 8^b. The water in this tank M forms a seal between the gas in the other tank and pipes in the system and the atmosphere. 70 The gas-condensing tank M', which is shown on Sheet 1, is nothing but an air-tight tank into which the wet-vacuum main 7 enters at a⁴, and from which it emerges on its way to the vacuum-pump D' at a⁵. A spray of water is admitted to the top of this tank at 7^c, and a pipe 7^b leads downwardly from it at 7^a into a well h filled with water, which serves to seal said pipe. The overflow from the well passes into a drain h', connected with a sewer. 80 Valves s admit compressed air or gas to the several storage-tanks from the main 9 and valves s' let out the air or gas from said tanks into the overflow-main 8, which communicates with the overflow-tank F. A valve x⁶ is 85 interposed in the vacuum-pump outlet-pipe 13^b for the purpose of shutting off communication between this pump and condenser L, when desired.

On Sheet 2 is shown the gas generator w w². 90 The gas passes from this generator into the heater W' through pipes 16^b and 16^a by opening valves r^8, r^9 . From the heater it passes into the main 16, and from there into the bottom of the digesters, by opening the corresponding inlet-valves x^7 . If heated air is wanted in the digesters instead of gas, the valve r^9 is closed and the valve x^8 opened, and if cold air is wanted for circulation through the digesters the valves r^8, r^9 , and 95 r^{12} are opened and valves r^{10} and r^{11} are closed.

All the tanks and digesters, the still, &c., are provided with thermometers, gage-glasses, pressure and vacuum gages; but these details are not shown in the drawings. 100

The following is a description of the operation of the apparatus, and for the sake of illustration it is assumed that all the digesters A', A², A³, and A⁴ are to be filled with raw wool, and that the plant has been previously 110 operated and is in condition for restarting. The wool is introduced into the digesters through necks a² of said digesters after the covers a³ have been removed. When the digesters are sufficiently loaded or charged, the 115 covers are replaced and screwed down. I would state here that each of the valves located in inlet-pipes 11 leading to the solvent-tanks are indicated by s, the corresponding outlet-valves s' being located in the outlet-pipes 12. Each of the digesters A' to A⁴ are provided with valves k v v' v³ v⁴ v⁶ v⁷ v⁸ x' x² and also connections, through which the digesters are adapted to intercommunicate, and 120 through which they are connected with the tanks, mains, &c. Thus, it will be seen that each digester has its respective series of valves.

In the following description, where specific reference is made to any of said valves with 13 respect to any one of the digesters A' A² A³ A⁴, it is to be understood that the valve indicated is the one located contiguous to the digester specified. The several valves v' are now

opened, thus putting all the digesters into direct communication with the wet-vacuum main 7 and the vacuum-pump D', which latter is now put into motion. At the same time the 5 valves x^8 and r^2 and the four valves x^7 are opened, and the air, which now rushes in at valve x^8 , is heated in W' and then passes into the main 16 and downwardly through the branches 16° and valves x^7 , into main 3 and enters the digesters through the lower inlets c^4 . The air is drawn upwardly through the wool by means of pump D', thereby heating the wool and carrying off part of the moisture which the latter contains. Instead of using the heater 15 W' to heat the air which is drawn through the wool, the bottom heaters a^6 , located inside of the digesters, can be used for the purpose, the valves x^7 in such case being kept closed and valves x^9 on branch connections 16° opened. 20 When the wool has been sufficiently warmed up, the air-valves x^8 or x^9 are closed; but the vacuum-pump D' is kept running, which soon produces a partial vacuum in the digesters, and under its influence and the heat retained 25 by the wool the remainder of the moisture which the latter contains distills off and the fibers are left in a dry condition and *in vacuo* without having been disturbed in the least or subjected to any excessive or injurious heat. 30 The vacuum-pump is now stopped and the valves x^8 or x^9 , as the case may be, being closed, all the valves x^7 and v' are also closed, while valve k on pipe f , entering the top head of digester A' at f , is opened, and also opening valve k' , which communicates with the corresponding outlet of storage-tank B⁴, which contains solvent which has been previously used four times. After closing the corresponding outlet-valve s' on top of tank B⁴ 35 the corresponding inlet-valve s which conveys compressed air or gas to said tank *via* branch pipe 11, is opened and the solvent in the said tank B⁴ is forced into the main 1, and from the latter into the digester top, which it enters at 40 f , as before stated. When the digester is full, which may be indicated by a gage-glass, the previously open valves k k' s ' are closed and valve s' opened, the latter letting the compressed air or gas flow from tank B⁴ into the 45 main 8, and from said main into the overflow-tank F, and thence into the trap-tank M, and through it to the atmosphere outside of the building. The valve v^7 (nearest digester A') on the supplementary lower main 3 is now 50 opened, and also the valve x' , located in a branch leading from the supplementary upper main 2 into the upper head of digester A², thereby putting the bottom of digester A' into communication with the top of digester A² at 55 f' through a riser 2^a, which connects said mains 3 and 2. The valve v^3 at or near the top of digester A' is next opened and compressed air or gas from the main 9 admitted to said digester. The solvent is forced out 60 through the bottom of digester A' into the top of digester A² by compressed air or gas, the latter then filling digester A', while digester

A² now in turn contains the solvent which came from storage-tank B⁴ *via* digester A'. The said valves v^7 and x' are next closed, 70 thereby cutting off communication between the bottom of digester A' and top of digester A². The valve k is again opened and the compressed air or gas valve v^3 closed. The valve x^2 between the tops of digester A' and A² is 75 then opened, thus putting the top of digester A' in communication with the top of digester A². The valve v^7 at the bottom of digester A² being now opened, and also valve x' at top of digester A³, the two latter digesters will 80 thereby be placed in communication with each other, and if now valve k' , which lets the solvent from tank B³ (which solvent has been used three times previously) into main 1 is opened, and outlet valve s' on top of said tank 85 closed, and the corresponding compressed air or gas inlet valve s opened, the solvent from tank B³ will thereby be driven into the top of digester A' and the compressed air or gas which it contains will be driven into the top 90 of digester A² and the solvent which digester A² previously contained will be driven out at the bottom of the latter into the top of digester A³, which in turn now holds the solvent first taken from the tank or reservoir B⁴, 95 while at the same time digester A² contains compressed air or gas and digester A' the solvent taken from tank B³. As soon as digester A' is full, valves k' and s are closed and the air or gas in tank B³ is allowed to escape through 100 its valve s' , &c., to the atmosphere, as before described. Valves k x^2 , (digester A'), v^7 , (digester A²), and x' (digester A³) are now closed and valves v^7 , (digester A³), x' , (digester A⁴), v^3 v^7 , (digester A'), x' , and x^2 (digester A²) are 105 opened. The solvent which originally came from tank B³ is driven by the compressed air or gas let in at v^3 from digester A' into digester A² through said valves v^7 and x' ; the compressed air or gas which was contained in 110 digester A² is in turn driven into digester A³ through said valve x^2 , and the solvent in digester A³, which originally came from tank B⁴ is in turn driven into the last digester A⁴ through said opened valves v^7 and x' . We 115 now have compressed air or gas in digester A', the solvent from tank B³ in digester A², compressed air or gas in digester A³, and the solvent which came from tank B⁴ in digester A⁴. The said last-opened valves v^7 , x' , v^3 , v^7 , 120 x' , and x^2 are now closed and the valves k x^2 , (digester A'), v^7 , (digester A²), x' x^2 , (digester A³), v^6 , (digester A⁴), and v^5 (communicating with tank B⁵) are opened after the valve s' , leading from tank B, has been closed and the 125 corresponding inlet-valve s to said tank and outlet-valve k' from said tank have been opened. The compressed air or gas admitted to tank B² through its valve s drives the solvent (which has been used twice before) into 130 the main 1 through said open valve k' and through corresponding valve k into the top of digester A'. The air or gas previously contained in digester A' then passes into digester

A² through the connecting-valve x^2 and drives out the solvent which originally came from tank B³ into digester A³ through the corresponding said open valves v^7 and x' , and the compressed air or gas which was contained in digester A³ escapes into digester A⁴ through the adjacent valve x^2 , thereby driving out into the storage-tank B⁵ (for saturated solvent 5) through valve v^6 , main 4, and corresponding inlet-valve v^5 the solvent which originally came from tank B⁴. Digester A' now contains solvent which has been used twice and was stored in tank B², digester A² contains compressed air or gas, digester A³ contains the solvent which has been used three times and was stored in tank B³, and digester A⁴ contains nothing but the wool and air or gas at or near atmospheric pressure, for the compressed air or gas which went from digester A³ into digester A⁴ followed the solvent into tank B⁵ through valves v^6 and v^5 and escaped from said tank through valve s' , &c., into the atmosphere. Now, valves s and k' , communicating with tank B², having been closed and outlet-valve s' opened as soon as digester A' had been filled with solvent from said tank B², the said open valves k x^2 , (digester A',) v^7 , (digester A²,) x' x^2 , (digester A³,) v^6 , (digester A⁴,) and v^5 (communicating with tank B⁵) are closed and valves v^3 v^7 , (digester A',) x' x^2 , (digester A²,) v^7 , (digester A³,) x' v^4 (digester A⁴) are opened. The solvent from digester A', which originally came from tank B², is driven by the compressed air or gas entering through valve v^3 , (digester A',) into the top of digester A² through said open valves v^7 and x' last referred to. The compressed air or gas which this digester A² contains is now driven into the top of digester A³ through valve x^2 , (digester A²,) and the solvent which digester A³ contains, and which originally came from tank B³, is driven into digester A⁴ through the adjacent valves v^7 and x' , the atmospheric air or gas contained in digester A⁴ at the same time making its escape through valve v^4 (digester A⁴) into the overflow or air or gas outlet main 8, communicating with tank F and trap-tank M. Digester A' now contains compressed air or gas, digester A² the solvent which came from tank B², digester A³ compressed air or gas, and digester A⁴ the solvent which came from tank B³. The first valve v^3 having been closed as soon as digester A' was empty, the said open valves v^7 , (digester A',) x' x^2 , (digester A²,) v^7 , (digester A³,) x' v^4 (digester A⁴) are now again closed and valves s , (leading to tank B',) k k x^2 , (digester A',) v^7 , (digester A²,) x' x^2 , (digester A³,) v^6 , (digester A⁴,) and v^5 s' , (leading to and from tank B⁴,) are opened. When thus adjusted, the solvent contained in tank B', and which has been used once before, is now driven by the compressed air or gas let into the tank at s into main 1 through the corresponding valve k' and through the adjacent valve k into the top of digester A'. The compressed air or gas contained in the latter digester escapes into

digester A² through the first valve x^2 , and the solvent which is contained in this digester, and which originally came from tank B², is driven into digester A³ through valves v^7 , (digester A²) and x' , (digester A³.) The air or gas contained in digester A³ is thereby driven out and on top of the solvent contained in digester A⁴ through valve x^2 , (digester A³,) and this solvent, which originally came from tank B³, is, after it has been thus used three times in previous operations, now returned to tank B⁴ (which is the receptacle for solvent having been used four times) through valve v^6 (digester A⁴), main 4, and valve v^5 , leading to tank B⁴. The compressed air or gas following the solvent escapes through valve s' . The previously open valves v^5 v^6 , (digester A⁴,) x^2 x' , (digester A³,) v^7 , (digester A²,) x^2 , (digester A¹,) k , k' , and s being closed, digester A' will be found to contain solvent from tank B'. Digester A² contains compressed air or gas, digester A³ the solvent which came from tank B², and digester A⁴ contains air or gas at or near atmospheric pressure. Of course the charge of wool is still retained in all the digesters. Valves v^3 v^7 , (digester A',) x' x^2 , (digester A²,) v^7 , (digester A³,) and x' v^4 (digester A⁴) are now opened and the solvent contained in digester A' is driven by the compressed air or gas (let in through first valve v^3) into digester A² through said valves v^7 and x' . The compressed air or gas contained in digester A² is driven into digester A³ through valve x^2 . The solvent in digester A³, and which originally came from tank B², is driven into digester A⁴ through corresponding valves v^7 and x' , and the atmospheric air or gas which this latter digester contained is driven out through valve v^4 , communicating with the main 8. Upon closing valve v^3 as soon as digester A' was empty the said valves v^7 , (digester A',) x' x^2 , (digester A²,) v^7 , (digester A³,) x' and v^4 (digester A⁴) are now closed, and we find that digester A' contains compressed air or gas, digester A² solvent taken from tank B', digester A³ compressed air or gas, and digester A⁴ solvent taken from tank B².
The wool contained in digester A' having now been thoroughly percolated with solvents which had been previously used four times, three times, twice, and once, respectively, it is now ready to be rinsed off with clean or pure solvent, and in order to effect such operation the digester A' is put into communication with tank B, which contains pure or unused solvent, and the following valves are opened: k s k x^2 , (digester A',) v^7 , (digester A²,) x' x^2 , (digester A³,) v^6 , (digester A⁴,) and v^5 s' , the two latter communicating with tank B³. The pure solvent is driven out of tank B by the compressed air or gas admitted through inlet-valve s . It enters the main 1 through corresponding valve k' and digester A' through adjacent valve k . The compressed air or gas in digester A' enters digester A² through first intermediate valve x^2 . The solvent in diges-

ter A² is driven out through valve v⁷ (digester A²) and enters digester A³ through valve x', (digester A³.) The compressed air or gas in digester A³ is driven out into digester A⁴ through valve x², (digester A³.) The solvent in digester A⁴, which originally came from tank B², is driven into storage-tank B³ (which is the receptacle for solvent having been used three times) through valve v⁶, (digester A⁴.)

5 main 4, and valve v⁵, leading to said tank B³. The compressed air or gas following the solvent into the last-named tank escapes through its outlet-valve s'. Valves k' and s having been closed as soon as the digester A' was 10 full, the before open valves k, x², v⁷, x', x², v⁶, v⁵, and s' are closed. We now have pure solvent in digester A' from tank B, compressed air or gas in digester A², solvent from tank B' in digester A³, and atmospheric air or gas 15 in digester A⁴. The solvent is next moved as follows: The several valves v⁸v⁷, (digester A'), x'x², (digester A²), v⁷, (digester A³), and x'v⁴, (digester A⁴) are now opened and the pure solvent 20 is driven from digester A' by compressed air or gas let in at v⁸ into the top of said digester. It passes thence into digester A² through said open valves v⁷ and x', and the compressed air or gas which this digester contains is driven into digester A³ through valve x², while the 25 solvent in digester A³, which originally came from tank B', escapes through valve v⁷ (digester A³) and enters the digester A⁴ through valve x', the air or gas contained in this latter digester escaping through valve v⁴ 30 into the main 8. Valve v³ (digester A') having been closed as soon as digester A' was freed from solvent, the valves v⁷, (digester A'), x'x², (digester A²), v⁷, (digester A³), x'v⁴ (digester A⁴) are now closed, and we 35 have in digester A' wool which has been washed with four lots of solvent and rinsed with pure solvent, and is surrounded with compressed air or gas. Digester A² contains wool immersed in pure solvent, digester A³ contains wool surrounded with compressed air or 40 gas, and digester A⁴ contains wool immersed in solvent coming from tank B'. Digester A' is now put in communication with tank B' (which is the receptacle for solvent having 45 been used once) by opening valves v⁶, (digester A'), v⁵, and outlet-valve s', communicating with the tank. The compressed air or gas contained in digester A' rushes through the wool (carrying before it remainders of solvent adhering to the fibers) out through said valve v⁶, main 4, and valve v⁵, and escapes into the main 50 8 through valve s', the solvent carried along by the air or gas remaining in tank B'. The passage of compressed air or gas through the 55 wool can be continued as long as necessary or desirable by simply opening the first valve v³, (digester A'), communicating with compressed air or gas main 9. The valves v⁸, (digester A²), v⁷, (digester A³), x'x², (digester A⁴), 60 v⁶, (digester A⁴), and v⁵ and s' (tank B²) are now opened and the compressed air or gas let into digester A² through said valve v⁸ forces the

pure solvent out of this digester into digester A³ through valves v⁷ and x'. The compressed air or gas contained in digester A³ enters digester A⁴ through valve x², and the solvent contained in digester A⁴, and which originally came from tank B', now finds its way to tank B² (which is the receptacle for solvent having been used twice) through corresponding valve v⁶, main 4, and valve v⁵. The compressed air or gas which follows the solvent escapes through valve s', leading from tank B² into main 8. Valve v³ having been closed as soon as digester A² was empty, the said valves v⁷, 80 (digester A²), x'x², (digester A³), v⁶, (digester A⁴), and v⁵, and s' are closed. Digester A² is then put in communication with tank B' by opening valve v⁶, (digester A²), valves v⁵ and s', leading to tank B', being opened and the compressed air or gas contained in said digester forces itself through the wool (carrying with it solvent adhering to the fibers) and escapes through said valve v⁶, main 4, valves v⁵, and s' into the main 8, while the solvent, which is 85 carried along by the air or gas, deposits itself in tank B'. The passing of compressed air or gas through the wool can be continued as long as desired by opening valve v⁸, (digester A².) We have now in digesters A' and A² 90 wool which has been treated with four lots of solvent and rinsed with pure solvent. In digester A³ we have wool immersed in pure solvent and in digester A⁴ wool surrounded by air or gas at or near atmospheric 95 pressure. Valves v⁸, (digester A²), v⁷, (digester A³), x', (digester A⁴) and v⁴ (digester A⁴) are now opened (valves v⁵ and s', leading to and from tank B', remaining open) and the compressed air or gas, entering digester A³ at 100 v⁸, drives the pure solvent from digester A³ into digester A⁴ through valves v⁷ and x', the atmospheric air or gas contained in digester A⁴ escaping into the main 8 through valve v⁴, (digester A⁴.) Valve v³ having been closed 105 as soon as digester A² was empty, said valves v⁷, x', and v⁴ are also closed. Digester A³ is put in communication with the tank B' by opening valve v⁶ (digester A³) and compressed air or gas is blown through the wool 110 in the same manner as described in relation to digesters A' A². We now have in digesters A', A², and A³ wool upon which the treatment with the solvents has been completed and in digester A⁴ wool immersed in pure solvent. 115 Now, upon opening valve v⁶ (digester A⁴) the digester A⁴ is put into communication with tank B' through main 4 and corresponding valve v⁵ and the solvent is forced out of digester A⁴ into tank B' by opening the compressed air or gas valve v³ at the top side of 120 digester A⁴, and when this digester has been emptied of its solvent-compressed air or gas is blown through the wool in the same manner as described in relation to digesters A' 125 and A². We now have in all the digesters wool which has been treated with four different lots of solvent and all rinsed with pure solvent. In tank B⁵, we have the solvent 130

which came out of tank B⁴, after having been used four times previously to the last time, and is now sufficiently charged with wool-fat to warrant redistilling. In tank B⁴ we have 5 the solvent which was in tank B³ when it had been used three times, but is now in the tank containing solvent having been used four times. In tank B³ is the solvent which came from tank B² when it had been used twice, 10 but now it has been used three times. In tank B² is the solvent, which came originally from tank B', after having been used once, but it now has been used twice. In tank B' is what came from tank B as pure solvent, but which 15 is now classed as having been used once. Thus it will be seen that each of the several solvents has been advanced once. The wool being now ready to be entirely freed from any solvent which still adheres to the fibers, 20 all the valves which were previously open, and through which valves the digesters were made to communicate with any of the mains or with each other, are now closed and the four valves v v v v over the digesters are 25 opened, thus putting them in communication with the dry-vacuum main 6 and the dry-vacuum pump D. The valve x¹¹, which allows the pump D to discharge into the pipe 13^b, is also opened and so is valve x⁶, which 30 puts said pump in communication with the condenser L through the piping 13 and valve r, which latter is open. The outlet from the condenser is put in communication with tank B (which now may be either empty or 35 only partially filled) by opening the valve v⁹ and the valve v¹⁰, communicating with said tank. The vacuum-pump D is put in motion, steam being at the same time turned onto the bottom heaters a⁶ inside of the digesters. Under 40 the influence of heat and vacuum thus produced the solvent remaining in the wool soon evaporates and is drawn from the bottom of the digesters upwardly through the wool into the dry-vacuum main 6, and pump D 45 forces the vaporized solvent into the condenser through the said piping 13^b and 13 and valve r. The condensed vapors pass from the condenser in the form of liquid solvent through valve v⁹ and enter tank B through 50 said valve v¹⁰, communicating with the tank. This distillation of the solvent adhering to the wool is kept up until it is fully completed, which is indicated by the vacuum-gages on the digesters. The pump D is then stopped 55 and the four valves v, connecting the digesters with main 6, are closed and the four oppositely-located valves v' are opened and the wet-vacuum pump D' started, the four air-valves x⁹ being also opened at the same time. 60 The air which is thus drawn through the wool removes from it any trace of odor of the solvent which may still be perceived in the fibers, and this process can, if desired, be accelerated by turning on a small jet of steam 65 into the bottoms of the digesters. The wool having now been practically freed from its fatty and resinous impurities, and also being

in a dry condition and free from solvent, is now ready to be removed from the digesters, for which purpose the upper and lower digester-doors b b have been provided, and to be rinsed in water. This latter operation is performed at a moderate temperature in machines such as are now generally used for the scouring of wools. I prefer, however, to use 70 machines having three or four bowls, because, although what few impurities now remaining on the fibers are either soluble in water or are removed by the mechanical action of the chines, it requires less time and less heat to 75 do the work properly with machines of this description. In using machines with three or four bowls the liquor contained in the first bowl soon becomes heavily charged with impurities and the potash salts contained in the 80 wool. This liquor is then run into an evaporating apparatus and the liquor from the second bowl is run into the first bowl, the liquor of the third bowl is run into the second bowl, and the liquor from the fourth bowl is run 85 into the third, while clear water is put into the fourth, and this process is kept up indefinitely, so that all the potash salts, ammonia, and other products which can be utilized as fertilizers are recovered as by-products of the 90 wool-washing, as well as the fatty and resinous matters carried off by the solvent, and of which I will make a further mention. The wool emerging from the machines, in which it has been thus rinsed with water, (without the 95 admixture of soap or alkali,) is perfectly clean and softer and stronger than wool of the same class which has been scoured in alkaline or soap solutions. In some instances, however, it is found beneficial to use a light neutral soap 100 solution in the third or fourth bowl, in order to feed or lubricate the wool. When this is practiced, the liquor from the first and second bowls only is evaporated.

In describing the treatment of the fibers 105 with solvent it will have been seen that I have represented and set forth a process wherein solvent contained in a digester is replaced by compressed air or gas, this air or gas being replaced by other solvent, this solvent in turn 110 by air or gas, and so on, the charge of solvent when entering one digester pushing the compressed air or gas into another digester, said compressed air or gas forcing the solvent out of this second digester into a third digester, 115 from which it forces the compressed air or gas into a fourth digester, &c.; or, in other words, the filling of one digester influences the whole series of digesters after they have once been filled. It is evident that the treatment with 120 solvents can be accomplished in a different manner, and that the solvent after being used in one digester can be returned to the storage-tank from which it came, then forced therefrom into the second digester, then again returned to the storage-tank and forced through 125 the third digester, &c., and this can be continued with the different grades of solvent contained in the sundry tanks until they each 130

have performed their work and absorbed sufficient fatty and resinous matter to warrant of their taking their new place in the series of storage-tanks, as I have heretofore described.

5 The solvent, instead of being forced from the bottom of one digester into the top of another digester, can just as well, if desired, be forced into the bottom of any other digester by manipulating the several valves v^7 and v^8 , 10 since all the digesters are intercommunicating both at the top and bottom, and they also communicate with all the mains and storage-tanks in the system, so that any digester can be reached from any tank or any tank from 15 any digester.

I would state that the necessity of the primary drying of the fibers which I have described, the necessity of their treatment with solvent either *in vacuo* or at atmospheric or 20 higher pressure, the number of different baths of charged solvent to which they are subjected, as well as the number of rinsings they get with pure solvent, depends wholly upon the condition and the nature of the 25 fibers under treatment, and that the steps as described are only one way of operating the apparatus out of a good many combinations which will suggest themselves to the practical scourer, according to the nature and condition 30 of the fibers which he is called upon to treat.

In some cases, in order to make certain resinous or glutinous impurities existing on the fibers more readily soluble in solvents or for the purpose of destroying any existing 35 vegetable matter, it may be desirable to treat the animal fibers with acid vapors or an acid gas—such as acetic-acid vapors, hydrochloric-acid gas, &c.—either before the treatment with solvent or after a partial treatment of 40 the fibers with a solvent. In such cases the gas may be generated in W W' , the same forming a part of the apparatus. The gas is drawn through the wool in the digesters by putting the latter in communication with the 45 wet-vacuum pump D' and main 7 and opening the four valves v' v' v' v' and r^x r^y r^z and x^1 x^2 x^3 x^4 . The gas or vapor enters the branch pipe 16^a after leaving the generator W , and, passing through said open valves r^x and r^y , 50 enters the heater W' , where it can be heated, if necessary. From the heater it passes into the main 16, and from there into the bottom of the digesters through the said open valves x^4 . The gas is drawn through the material in the 55 digesters and escapes into the main 7 through the four digester-valves v' . The main 7 passes into and through the gas-condensing tank M' , wherein any acid gas or vapor soluble in water is retained and therefore prevented 60 from corroding the pump D' .

The solvent contained in tank B^5 , which is supposed to have attained a sufficient degree of saturation with the fatty and resinous matter contained in wool or other similar animal fibers, and making it undesirable for further use in the treatment of such fibers, is forced from said tanks into the settling-tank I,

wherein any suspended matter contained in such solvent is allowed to settle before the solvent is let into the still H for rectification. 70

Upon letting compressed air or gas into tank B^5 through corresponding inlet-valve s , the valves k' , r^5 , and w^5 are opened, thereby forcing the solvent into settling-tank I, and when the suspended matter it contains has 75 settled to the bottom it (the freed solvent) is run into the still H by closing the valves previously opened and letting compressed air or gas in at the top of the settling-tank through the valve w' . The solvent passes from said 80 settling-tank through any one of the series of valves r' and enters the still through piping 18 and valve r^2 .

When the sediment in the settling-tank has accumulated to any considerable depth, it is 85 separated from the solvent by letting out the mixture from the tank through valve r^7 and piping 21 into a filter K . The sediment is deposited upon the filter-bed and the solvent passed through the filtering material into the 90 pipe 10, and from the latter into the tank B^5 through valved connection 10^b, provision being made for removing the sediment from the filter when necessary.

The still H is provided interiorly with a 95 steam-coil, and directly communicates with the condenser L through valve r^{10} , piping 13, and valve r . Indirectly it also communicates with said condenser through valve r^{11} , piping 6 and 13^a, vacuum-pump D , piping 13 and 13^b, 100 and valves x^{11} , x^6 , and r . The rectification of the solvent is accomplished by distillation; but instead of applying a strong heat to it through the steam-coils contained in the stills and driving the vapors over from them 105 through the direct communication indicated above, I prefer to use heat and vacuum combined and communicate from the stills to the condensers through a vacuum-pump, as indicated above, because the solvent passes over 110 at a lower temperature and the wool-fat is therefore obtained in better condition.

From the condenser the liquid rectified solvent enters tank B , as was described in the distillation of the solvent remaining on the fibers 115 contained in the digesters. When all the solvent contained in the still H has been distilled, there will remain in this still the fatty and resinous matters which the solvent extracted from the fibers through which it percolated, which matter is commonly called "pure" 120 wool-fat to distinguish it from the product obtained from the treatment of wool-wash suds, which latter contains soap-fats and other constituents not contained in the fat extracted 125 from the wool with solvent. This product, (said fatty and resinous matter,) while still in a fluid state, is run into the grease-storage tank E . The fluid fat leaves the still through valve r^4 and piping 15, which leads it to said 130 storage-tank. The grease-tank E is emptied while the fat is in a fluid condition (steam-coils being provided for the purpose in the bottom of the tank) by means of compressed

air or gas introduced through valve b^6 , the fat escaping into convenient receptacles through valve n^2 , provided for the purpose at the bottom of said tank.

5. I claim as my invention—

1. The process of freeing animal fibers from their fatty and resinous impurities, the same consisting in subjecting said fibers while retained in a closed digester to the action of solvents for such impurities, then removing said solvent from the digester, then expelling, in liquid form, the bulk of the solvent still adhering to the fibers by the action of a compressed gas forced through them, and then 15 freeing the fibers from the remaining adhering solvent, substantially as described and for the purpose set forth.

2. The process of freeing animal fibers from their fatty and resinous impurities, the same 20 consisting in subjecting said fibers while retained in a closed digester to the action of solvents for such impurities, then removing said solvent from the digester, then expelling, in liquid form, the bulk of the solvent still adhering to the fibers by the action of a compressed gas forced through them, and then 25 freeing the fibers from the remaining adhering solvent by distillation under the influence of heat and vacuum while contained in said 30 digester, substantially as described and for the purpose set forth.

3. The process of freeing animal fibers from their fatty and resinous impurities, the same 35 consisting in subjecting said fibers while retained in a closed digester to the action of solvents for such impurities, then removing said solvent from the digester, then expelling, in liquid form, the bulk of the solvent still adhering to the fibers by the action of a compressed gas forced through them, then 40 freeing the fibers from the remaining adhering solvent, and then deodorizing said fibers by drawing air or steam or both through them, substantially as described and for the purpose 45 set forth.

4. The process of freeing animal fibers from their fatty and resinous impurities, the same 50 consisting in subjecting said fibers while retained in a closed digester to the action of solvents for such impurities, then expelling the solvent in liquid form from the contents 55 of the digester by the action of compressed gas, then freeing said fibers from any adhering solvent by distillation under the influence of heat and vacuum while contained in said digester, and then deodorizing said fibers, substantially as described and for the purpose set forth.

5. The process of freeing animal fibers from 60 their fatty and resinous impurities, the same consisting in making the first impregnation of said fibers with solvents for such impurities *in vacuo*, then continuing the subsequent treatments with solvents at atmospheric or higher 65 pressure, and then freeing said fibers from any adhering solvent by distillation while con-

tained in a closed digester, substantially as described and for the purpose set forth.

6. The process of freeing animal fibers from their fatty and resinous impurities, the same 70 consisting in making the first impregnation of said fibers with solvents for such impurities *in vacuo*, then continuing the subsequent treatments with solvents at atmospheric or higher 75 pressure, and then freeing said treated fibers from any adhering solvent by distillation under the influence of heat and vacuum, substantially as described and for the purpose set forth.

7. The process of freeing animal fibers from 80 their fatty and resinous impurities, the same consisting in making the first impregnation of said fibers with solvents for such impurities *in vacuo*, then continuing the subsequent treatments with solvents at atmospheric or higher 85 pressure, then freeing said fibers from any adhering solvent by distillation while contained in a closed digester, and then deodorizing said fibers by drawing air or steam or both through them, substantially as described 90 and for the purpose set forth.

8. The process of freeing animal fibers from their fatty and resinous impurities, the same 95 consisting in making the first impregnation of said fibers with solvents for such impurities *in vacuo*, then continuing the subsequent treatments with solvents at atmospheric or higher pressure, then freeing said fibers from any adhering solvent by distillation under the influence of heat and vacuum, and then 100 deodorizing said fibers by drawing air or steam or both through them, substantially as described and for the purpose set forth.

9. The process of freeing animal fibers from their fatty and resinous impurities, the same 105 consisting in subjecting said fibers while retained in a closed digester to alternate contacts, first with solvents for such impurities each of a different degree of saturation and then with compressed gas, the function of 110 which is to remove the bulk of the solvent in liquid form, and then freeing said fibers from any adhering solvent, substantially as described and for the purpose set forth.

10. The process of freeing animal fibers 115 from their fatty and resinous impurities, the same consisting in subjecting said fibers while retained in a closed digester to alternate contacts, first with solvents for such impurities each of a different degree of saturation and 120 then with compressed gas, the function of which is to remove the bulk of the solvent in liquid form, and then freeing said fibers from any adhering solvent by distillation under the influence of heat and vacuum while contained 125 in said digester, substantially as described and for the purpose set forth.

11. The process of freeing animal fibers from their fatty and resinous impurities, the same 130 consisting in subjecting said fibers while retained in a closed digester to alternate contacts, first with solvents for such impurities

each of a different degree of saturation and then with compressed gas, the function of which is to remove the bulk of the solvent in liquid form, then freeing said fibres from any adhering solvent, and then deodorizing said fibers, substantially as described and for the purpose set forth.

12. The process of freeing animal fibers from their fatty and resinous impurities, the same consisting in subjecting said fibers while retained in a closed digester to alternate contacts, first with solvents for such impurities each of a different degree of saturation and then with compressed gas, the function of which is to remove the bulk of the solvent in liquid form, then freeing said fibers from any adhering solvent by distillation under the influence of heat and vacuum while contained in said digester, and then deodorizing said fibers by drawing air or steam or both through them, substantially as described and for the purpose set forth.

13. The process of freeing animal fibers from their fatty and resinous impurities, the same consisting in drying said fibers while contained in a closed digester by aspirating air through them, then subjecting said fibers to the action of solvents for such impurities, then freeing said fibers from any adhering solvent by distillation while contained in said digester, and then deodorizing said fibers by drawing air or steam or both through them, substantially as described and for the purpose set forth.

14. The process of freeing animal fibers from their fatty and resinous impurities, the same consisting in drying said fibers while contained in a closed digester by aspirating air through them, then subjecting said fibers to the action of solvents for such impurities, then freeing said fibers from any adhering solvent by distillation while contained in said digester under the influence of heat and vacuum, and then deodorizing said fibers by drawing air or steam or both through them, substantially as described and for the purpose set forth.

15. The process of freeing animal fibers from their fatty and resinous impurities, the same consisting in drying said fibers while contained in a closed digester by drawing air through them and submitting said fibers to the combined action of heat and vacuum, then treating said fibers with solvents for such impurities, and then freeing said fibers from any adhering solvent by distillation while contained in said digester, substantially as described and for the purpose set forth.

16. The process of freeing animal fibers from their fatty and resinous impurities, the same consisting in drying said fibers while contained in a closed digester by drawing air through them and submitting said fibers to the combined action of heat and vacuum, then treating said fibers with solvents for such impurities, and then freeing said fibers from any adhering solvent by distillation while

contained in said digester under the influence of heat and vacuum, substantially as described and for the purpose set forth.

17. The process of freeing animal fibers from their fatty and resinous impurities, the same consisting in drying said fibers while contained in a closed digester by drawing air through them and submitting said fibers to the combined action of heat and vacuum, then treating said fibers with solvents for such impurities, then freeing said fibers from any adhering solvent by distillation while contained in said digester, and then deodorizing said fibers by drawing air or steam or both through them, substantially as described and for the purpose set forth.

18. The process of freeing animal fibers from their fatty and resinous impurities, the same consisting in drying said fibers while contained in a closed digester by drawing air through them and submitting said fibers to the combined action of heat and vacuum, then treating said fibers with solvents for such impurities, then freeing said fibers from any adhering solvent by distillation under the influence of heat and vacuum while contained in said digester, and then deodorizing said fibers by drawing air or steam or both through them, substantially as described and for the purpose set forth.

19. The process of freeing animal fibers from their fatty and resinous impurities, the same consisting in drying said fibers while contained in a closed digester by aspirating air through them, then subjecting said fibers to alternate contacts, first with solvents for such impurities each of a different degree of saturation and then with compressed gas, the function of which is to remove the bulk of the solvent in liquid form, and then freeing said fibers from any adhering solvent by distillation while contained in said digester, substantially as described and for the purpose set forth.

20. The process of freeing animal fibers from their fatty and resinous impurities, the same consisting in drying said fibers while contained in a closed digester by aspirating air through them, then subjecting said fibers to alternate contacts, first with solvents for such impurities each of a different degree of saturation and then with compressed gas, and then freeing said fibers from any adhering solvent by distillation under the influence of heat and vacuum while contained in said digester, substantially as described and for the purpose set forth.

21. The process of freeing animal fibers from their fatty and resinous impurities, the same consisting in drying said fibers while contained in a closed digester by aspirating air through them, then subjecting said fibers to alternate contacts, first with solvents for such impurities each of a different degree of saturation and then with compressed gas, then freeing said fibers from any adhering solvent by distillation while contained in said

digester, and then deodorizing said fibers by drawing air or steam or both through them, substantially as described and for the purpose set forth.

5 22. The process of freeing animal fibers from their fatty and resinous impurities, the same consisting in drying said fibers while contained in a closed digester by aspirating air through them, then subjecting said fibers 10 to alternate contacts, first with solvents for such impurities each of a different degree of saturation and then with compressed gas, the function of which is to remove the bulk of the solvent in liquid form, then freeing said 15 fibers from any adhering solvent by distillation under the influence of heat and vacuum while contained in said digester, and then deodorizing said fibers by drawing air or steam or both through them, substantially as described and for the purpose set forth.

23. The process of freeing animal fibers from their fatty and resinous impurities, the same consisting in drying said fibers while contained in a closed digester by drawing air 25 through them, then submitting said fibers to the combined action of heat and vacuum, then to alternate contacts, first with solvents for such impurities each of a different degree of saturation and then with compressed gas, and 30 afterward freeing said fibers from any adhering solvent by distillation while contained in said digester, substantially as described and for the purpose set forth.

24. The process of freeing animal fibers 35 from their fatty and resinous impurities, the same consisting in drying said fibers while contained in a closed digester by drawing air through them, then submitting said fibers to the combined action of heat and vacuum, then 40 subjecting said fibers to alternate contacts, first with solvents for such impurities each of a different degree of saturation and then with compressed gas, and afterward freeing said 45 fibers from any adhering solvent by distillation under the influence of heat and vacuum and while contained in said digester, substantially as described and for the purpose set forth.

25. The process of freeing animal fibers 50 from their fatty and resinous impurities, the same consisting in drying said fibers while contained in a closed digester by drawing air through them, then submitting said fibers to the combined action of heat and vacuum, then 55 subjecting said fibers to alternate contacts, first with solvents for such impurities each of a different degree of saturation and then with compressed gas, then freeing said fibers from any adhering solvent by distillation 60 while contained in said digester, and then deodorizing said fibers by drawing air or steam or both through them, substantially as described and for the purpose set forth.

26. The process of freeing animal fibers 65 from their fatty and resinous impurities, the same consisting in drying said fibers while

contained in a closed digester by drawing air through them, then submitting said fibers to the combined action of heat and vacuum, then subjecting said fibers to alternate contacts, 70 first with solvents for such impurities each of a different degree of saturation and then with compressed gas, then freeing said fibers from any adhering solvent by distillation under the influence of heat and vacuum while contained 75 in said digester, and then deodorizing said fibers by drawing air or steam or both through them, substantially as described and for the purpose set forth.

27. The process of freeing animal fibers 80 from their fatty and resinous impurities, the same consisting in treating said fibers with solvents for such impurities while contained in a closed digester, then replacing said solvents by compressed gas, and subjecting said 85 fibers to alternate contacts with compressed gas and solvents of different degrees of saturation, then rinsing said fibers with pure solvent and then freeing them from any adhering solvent by distillation while contained in said 90 digester, substantially as described and for the purpose set forth.

28. The process of freeing animal fibers from their fatty and resinous impurities, the same consisting in treating said fibers with 95 solvents for such impurities while contained in a closed digester, then replacing said solvent by compressed gas and subjecting said fibers to alternate contacts with compressed gas and solvents of different degrees of saturation, then rinsing said fibers with pure solvent and then freeing them from any adhering solvent by distillation while contained in said 100 digester under the combined action of heat and vacuum, substantially as described and 105 for the purpose set forth.

29. The process of freeing animal fibers from their fatty and resinous impurities, the same consisting in treating said fibers with solvents for such impurities while contained 110 in a closed digester, then replacing said solvent by compressed gas and subjecting said fibers to alternate contacts with compressed gas and solvents of different degrees of saturation, then rinsing said fibers with pure solvent and freeing them from any adhering solvent by distillation while contained in said 115 digester, and then deodorizing them by drawing either air or steam or both through them, substantially as described and for the purpose 120 set forth.

30. The process of freeing animal fibers from their fatty and resinous impurities, the same consisting in treating said fibers with solvents for such impurities while contained 125 in a closed digester, then replacing said solvent by compressed gas and subjecting said fibers to alternate contacts with compressed gas and solvents of different degrees of saturation, then rinsing said fibers with pure solvent and then freeing them from any adhering solvent by distillation while contained in said 130

digester under the combined action of heat and vacuum, substantially as described and for the purpose set forth.

31. The process of freeing animal fibers from their fatty and resinous impurities, the same consisting in drying said fibers while contained in a closed digester by drawing air through them, then subjecting said fibers to the combined action of heat and vacuum, then making the first impregnation of said fibers with solvents while *in vacuo*, then replacing said solvent with compressed gas, then subjecting said fibers to alternate contacts with compressed gas and solvents of different degrees of saturation, then rinsing said fibers with pure solvent, and then freeing them from any adhering solvent by distillation while contained in said digester, substantially as described and for the purpose set forth.

32. The process of freeing animal fibers from their fatty and resinous impurities, the same consisting in drying said fibers while contained in a closed digester by drawing air through them and subjecting said fibers to the combined action of heat and vacuum, then making the first impregnation of said fibers with solvent while *in vacuo*, then replacing said solvent with compressed gas, then subjecting said fibers to alternate contacts with compressed gas and solvents of different degrees of saturation, then rinsing said fibers with pure solvent, and then freeing them from adhering solvent by distillation under the influence of heat and vacuum while contained in said digester, substantially as described and for the purpose set forth.

33. The process of freeing animal fibers from their fatty and resinous impurities, the same consisting in drying said fibers while contained in a closed digester by drawing air through them, and subjecting said fibers to the combined action of heat and vacuum, then making the first impregnation of said fibers with solvent while *in vacuo*, then replacing said solvent with compressed gas, then subjecting said fibers to alternate contacts with compressed gas and solvents of different degrees of saturation, then rinsing said fibers with pure solvent, then freeing them from any adhering solvent by distillation while contained in said digester, and then deodorizing said fibers by drawing air or steam or both through them, substantially as described and for the purpose set forth.

34. The process of freeing animal fibers from their fatty and resinous impurities, the same consisting in drying said fibers while contained in a closed digester by drawing air through them and subjecting said fibers to the combined action of heat and vacuum, then making the first impregnation of said fibers with solvent while *in vacuo*, then replacing said solvent with compressed gas, then subjecting said fibers to alternate contacts with compressed gas and solvents of different degrees of saturation, then rinsing said fibers

with pure solvent, then freeing them from any adhering solvent by distillation while contained in said digester under the combined action of heat and vacuum, and then deodorizing said fibers by drawing air or steam or both through them, substantially as described and for the purpose set forth.

35. In apparatus for freeing animal fibers from their fatty and resinous impurities, by volatile solvent, the combination of a closed digester, two or more solvent tanks for holding solvents of different degrees of saturation communicating at their tops through valved piping with the bottom of said digester and at their bottoms with the top of said digester, substantially as described.

36. In apparatus for freeing animal fibres from their fatty and resinous impurities, by volatile solvent, the combination of a series of digesters arranged in battery and in independent intercommunication at their tops and bottoms, a series of storage tanks for holding solvent of different degrees of saturation and pure solvent also independently intercommunicating, and valved piping connecting said digesters and tanks, arranged whereby any one or more of the said digesters and tanks are adapted for independent intercommunication at top and bottom, substantially as described.

37. In apparatus for freeing animal fibers from their fatty and resinous impurities, by volatile solvent, the combination of a closed digester, two or more storage tanks for solvent arranged to communicate with the top and bottom of the digester, valved inlet and outlet passages for said solvents, and valved piping communicating with said digester and tanks and with a source of compressed gas, substantially as described.

38. In apparatus for freeing animal fibers from their fatty and resinous impurities, by volatile solvent, the combination of a plurality of closed digesters arranged in battery and in independent intercommunication at their tops and bottoms, a series of storage tanks for solvents also independently intercommunicating with each other and with said digesters, and a source of compressed gas in communication with the digesters and tanks, substantially as described.

39. In apparatus for freeing animal fibers from their fatty and resinous impurities, by volatile solvent, one or more closed digesters, in combination with exhausting and condensing devices for solvent vapors connected therewith, a source of compressed gas, one or more reservoirs for solvents and a trap-tank or water-seal, substantially as described.

40. In apparatus for freeing animal fibers from their fatty and resinous impurities, by volatile solvent, one or more closed digesters, in combination with exhausting and condensing devices for solvent vapors connected therewith, a source of compressed gas, one or more reservoirs for solvents, a trap-tank or water-

seal and an overflow tank, substantially as described.

41. In apparatus for freeing animal fibers from their fatty and resinous impurities, by 5 volatile solvent, one or more closed digesters, in combination with exhausting and condensing devices for solvent vapors connected therewith, a source of compressed gas, one or more reservoirs for solvents, a trap tank or water seal, an overflow tank and a settling tank, substantially as described.

42. In apparatus for freeing animal fibers from their fatty and resinous impurities, by 15 volatile solvent, one or more closed digesters, in combination with exhausting and condensing devices for solvent vapors connected therewith, a source of compressed gas, one or more reservoirs for solvents, a trap tank or water seal, an overflow tank and a still, substantially as described.

43. In apparatus for freeing animal fibers from their fatty and resinous impurities, by 20 volatile solvent, one or more closed digesters, in combination with exhausting and condensing devices for solvent vapors connected therewith, a source of compressed gas, one or more reservoirs for solvents, a trap tank or water seal, an overflow tank and a gas generator, substantially as described.

44. In apparatus for freeing animal fibers, substantially as described.

45. In apparatus for freeing animal fibers 30 from their fatty and resinous impurities, by volatile solvent, one or more closed digesters, in combination with exhausting and condensing devices for solvent vapors connected therewith, a source of compressed gas, one or more 35 reservoirs for solvents, a trap tank or water seal, an overflow tank and a filter, substantially as described.

46. In apparatus for freeing animal fibers from their fatty and resinous impurities, by 40 volatile solvent, one or more closed digesters, in combination with exhausting and condensing devices for solvent vapors connected therewith, a source of compressed gas, one or more reservoirs for solvents, a trap tank or water 45 seal, an overflow tank and a gas generator, substantially as described.

In testimony whereof I have affixed my signature in presence of two witnesses.

EMILE MAERTENS.
